LOW-HEAD VERTICAL-SHAFT HYDRO-ELECTRIC SET

Charles Marie Fevre, Le Creusot, France, assignor to
Société des Forges et Ateliers du Creusot, Paris, France,
a French company

Application November 23, 1956, Serial No. 623,960

Claims priority, application France November 30, 1955

3 Claims. (Cl. 290—52)

The present invention relates to a new arrangement intended to reduce the diametrical dimensions of the spiral chamber in low-head vertical-shaft hydro-electric sets, which allows an appreciable reduction in civil engineering works, and consequently in the cost of installation.

It is known that the water passage cross-sections at each point of the spiral chamber are calculated as a function of the delivery and of the head available; the dimensions of the spiral chamber are thus determined on the one hand by the passage cross-sections to be provided, and on the other hand by the diameter about which the spiral chamber is developed.

According to the invention, the spiral chamber is developed about a central lining of which the maximum diameter is substantially equal to that of the moving wheel, the lower part of the lining being of a substantially truncated conical shape connected to the hub of the said wheel in such a way as to form the central core of the annular outlet duct of the spiral chamber, the said lining, which consists of a metallic caisson which may support the pivot of the unit, itself being supported at the inlet of the said duct by way of inclined pre-guiding blades, the blades of the distributor being articulated about axes inclined along a direction substantially normal to the truncated conical profile of the lining.

Two particular forms of embodiment of a hydro-electric set according to the invention are illustrated more or less diagrammatically in the attached drawing, and are described hereinafter by way of examples.

In the drawing:

Figure 1 is a vertical section through a set having a Kaplan turbine in which the alternator is situated above the metallic caisson.

Figure 2 is a vertical section through a set in which the alternator is situated inside the metallic caisson.

In these figures, 1 designates the turbine wheel mounted below a spiral chamber 2, which is accommodated in the concrete mass 3 of the station, and communicates directly with the upstream water level 4.

A metallic caisson 5 fitted in the concrete girder 6 is situated at the centre of the spiral chamber 2, of which the said concrete girder forms the ceiling; this caisson is supported on the foundations by way of the casing 7 of the turbine, by means of the girders 8 which form the fixed preguiding blades.

The upper part of the caisson 5 is cylindrical, while

2

the lower part 9 is contoured in such a manner as to be connected to the hub of the wheel, and to form the central core of an annular duct 10 of which the external wall is formed by the casing 7.

5 The blades 11 of the distributor are situated about this casing 7, and are articulated about axes substantially perpendicular to the central core of the said annular duct 10 in such a manner as to form a conical distributor of small diameter.

10 The lower part 9 of the caisson 5 carries the lower guide bearing 12 of the shaft 13 of the group.

In the embodiment illustrated in Figure 1, the pivot 14 of the set which may be any suitable type of combined radial and thrust bearing is situated inside the caisson 5,

15 with the fixed part 19 thereof bearing on a solid horizontal shoulder 19 of the caisson 5 to support wheel 1 in duct 10. The alternator consisting of the stator 16 and the rotor 17 is situated above the girder 6, which absorbs the reaction of the electrical torque of the alter-

20 nator.

According to the embodiment illustrated in Figure 2, the stator 16 of the alternator is situated inside the caisson 5, while the pivot 14 is situated at the top of caisson 5.

This arrangement lends itself particularly well to installation in a station of the pier type; in fact, it allows the plan measurements of each set to be reduced, and the feed of water from the inlet chamber to the turbine to be improved.

It must be understood that the set can be modified, or 30 completed by any useful accessories, without departing from the scope of the invention.

Furthermore, the invention is not limited to turbines of the type shown and is applicable to turbines which include mechanism for orienting the vanes and to turbines 35 having a Francis wheel which is used with a conical distributor.

What I claim is:

1. In a low-head vertical-shaft hydro-electric set including a turbine wheel having a hub, a spiral chamber, 40 an annular outlet duct for said chamber, a cylindrical metal caisson forming a central lining for said chamber and having a diameter substantially equal to the diameter of said wheel, a truncated conical portion of said caisson forming a central core for said outlet duct and fairing 45 into the hub of said wheel, inclined pre-guiding blades supporting said caisson in said chamber and distributor blades articulated about their long axis and substantially normal to the profile of said truncated conical portion, said wheel being mounted in said outlet duct.

50 2. A hydro-electric set as described in claim 1 in which said caisson supports the set when said wheel is in position in said duct.

3. A hydro-electric set as described in claim 1 including a generator having a stator and a rotor, said stator 55 being centered within said caisson.
